UNITED STATES PATENT OFFICE.

BENNETT SANBERG, OF NEW YORK, N. Y.

DESIGN FOR A LAMP CLUSTER.

Application filed April 25, 1924. Serial No. 9,404. Term of patent 14 years.

To all whom it may concern:

Be it known that I, BENNETT SANBERG, a citizen of the United States, residing at New York city, in the county of New York and State of New York, have invented a new, original, and ornamental Design for a Lamp Cluster, of which the following is a specification, reference being had to the accompanying drawing, forming part thereof.

In the drawings:—

Figure 1 is a side elevation.
Figure 2 is an end elevation.
Figure 3 is a top plan view.

I claim:—

The ornamental design for a lamp cluster, as shown.

BENNETT SANBERG.
